SWITCHBOARD PLUG

John J. Ziemianin, Jr., Chicago, Ill.

Application December 6, 1951, Serial No. 260,122

8 Claims. (Cl. 339—183)

1

This invention relates to terminal plugs comprising electrical conductors, and more particularly to a terminal plug for use in a telephone switchboard or the like.

Terminal plugs of the type adapted for use in telephone switch boards generally comprise a conductor plug adapted to be inserted in a jack holder which mounts plural terminal contacts electrically connected to a plural conductor cord. Such conductor plugs are generally of a reversible type in that the opposite end portions thereof are electrically identical and symmetrically configured. In the past, the various electrical conducting elements comprising the conductor plug have been separately milled prior to assemblage, and the same is true for the various insulators used to separate the conducting elements at the opposite end portions thereof. It is therefore an object of the present invention to eliminate such prior procedures by means of a novel blank which can be machined to a finished conductor plug in one operation and which can be provided with internal insulation by means of injection molding.

It is desirable that the conductor plug be reversible in the jack holder without need for knockdown or disassemblage of the parts comprising the jack holder, and it is therefore an object of the present invention to afford means whereby this may be accomplished. Moreover, in this connection, it is desirable that the plural terminal contacts be positioned on or in the jack holder by means other than fixed metallic retaining elements, and it is therefore an object of the present invention to confine rather than fix the terminal contacts relative to the jack holder.

Other objects of the present invention will be apparent from the following description and the drawings, particularly with respect to the novel method of manufacturing conductor plugs and the manner in which the terminal contacts are positioned in the jack holder.

In the drawings:

Fig. 1 is a plan view of a terminal plug embodying the features of the present invention, the outer shell being shown in section;

Fig. 2 is a sectional view taken substantially along the line 2—2 of Fig. 1 with certain parts shown in elevation;

Figs. 3, 4 and 5 are sectional views taken substantially along the lines 3—3, 4—4 and 5—5 of Fig. 2;

Fig. 6 is a sectional view similar to Fig. 2 but showing the conductor plug in elevation and broken away;

Fig. 7 is a sectional view similar to Fig. 6;

2

Fig. 8 is a sectional view taken substantially along the line 8—8 in Fig. 6;

Fig. 9 is a horizontal sectional view taken through the jack holder;

5 Figs. 10 and 11 are sectional views taken substantially along the lines 10—10 and 11—11 of Fig. 9;

Fig. 12 is a top plan view of the jack holder shown in Fig. 9;

10 Fig. 13 is a perspective view of a terminal contact;

Fig. 14 is a sectional view of a conductor plug blank; and

15 Fig. 15 is a sectional view taken substantially along the line 15—15 of Fig. 14.

In Figs. 1—14, the aspects of the present invention are illustrated as embodied in a terminal plug generally indicated at 20 which comprises a conductor plug 20 either end portion of which is adapted to be releasably and reversibly disposed in an inner housing or so-called jack-holder 40, the latter carrying several spaced-apart terminal contacts each provided with a contact spring which is adapted to engage a corresponding conducting section or element of the conductor plug. The conductor plug comprises terminal heads and collars paired with one another at the opposite ends thereof, such heads and collars being of electrically conducting material.

20 An elongated sleeve, also of electrically conducting material, extends between opposite pairs of heads and collars, and the collars, sleeve, and heads are insulated one from another. The jack holder 40 is generally cylindrical in shape and is 25 formed on its periphery with elongated, spaced-apart slots that permit radial movement of the contact springs relative to the jack holder during insertion and withdrawal of the conductor plug.

30 Each of the terminal contacts is connected to a lead-in conductor of a plural conductor cord, and the terminal contacts are mounted on the jack holder in such a manner as to be confined in position rather than fixed by screws or interconnecting conductors that ordinarily require tedious 35 manipulations during assemblage and disassemblage.

35 Referring to Figs. 1 and 2, the conductor plug, generally indicated at 20, is shown as being partially disposed in an internal chamber 41 of a tubular jack holder 40. An outer tubular housing or shell 60 surrounds the jack holder and tends to confine the terminal contacts as 50 in a manner to be described below. The outer housing 60 is open at one end to permit insertion of the plug 20 into the open end of the jack holder,

and the other end 62 of the housing 60 is partially closed being provided with an opening for receiving one end of a triple conductor cord 61. As best shown in Fig. 2, the conductor plug 20 is in the form of a substantially solid rod or cylinder the opposite end portions of which are symmetrically shaped and conductively identical so that the plug is adapted for reversal in the jack holder 40. The remote ends of plug 20 are provided with terminal heads 21 which are composed of electrical conducting material as for instance brass, and these heads 21 are insulated from enlarged diameter metallic collars 23 by means of hard rubber rings 22. The outer body portion of the plug 20 is in the form of an elongated conducting sleeve 28, the opposite ends of which are insulated from reduced diameter metallic collars 26 by other hard rubber rings 27, and in turn these inner collars 26 are each similarly insulated from corresponding outer collars 23 by insulating rings 24.

Ordinarily, the various conducting and insulating elements of a plug such as 20 are separately and accurately milled before being assembled. The present invention dispenses with such procedures and affords a novel blank and process by which the entire conductor plug can be machined in one operation, thus eliminating initial size tolerance considerations almost entirely. Moreover, since conductor plugs of this type embody internal insulators which must be molded or shaped separately within defined tolerances and then assembled manually, the present invention affords a method whereby the unfinished plug blank can be provided with internal insulation in a single step.

A blank 20A of the type embodied in the concept of the present invention is illustrated in Fig. 14 wherein the suffix A is used to designate unfinished or unmachined parts of the plug 20 previously considered in connection with Figs. 1 and 2. Thus, a central steel core 30 is formed with projections 31 of reduced diameter which are knurled as at 33. Concentric to but spaced radially from the steel core 30 is an internal steel sleeve 35 that is formed with a central opening 36 for a purpose to be described below. Concentric to but spaced radially from the steel sleeve 35 by bushing portions 25 on insulating rings 27A, is the outer bronze sleeve 28 previously considered. The ends of sleeve 35 project slightly beyond the insulating rings 27A so as to afford mounts for inner conducting collars 26A, the latter being insulated from outer metallic collars 23A by rubber rings 24A. It will be observed that the central bores in the collars 26A, 23A and the insulating ring 24A are of a diameter larger than that of the central core 30. A pair of brass bosses 21A are pressed over the knurls 33 on the projections 31 and are separated from the outer metallic collars 23A by insulating rings 22A.

The plug blank 20A is most easily assembled by first slipping one of the rings 27A over one end of the inner conducting sleeve 35, after which the outer conducting sleeve 28 is positioned on the bushing portion 25 of the thus-assembled ring 21A. The other insulating ring 27A is then forced over the other end of sleeve 35 and into firm engagement with the other end of sleeve 28. The inner collars 26A are mounted on the projecting ends of sleeve 35, and then the rubber rings 24A, outer collars 23A, and rubber insulating rings 22A are arranged about the projections 31 of the core 30. Finally, the bosses 21A are pressed over the knurls 33, and the outer collars and insulat-

ing rings which are loose on projection 31 are forced toward the inner collars 26A to limit positions. After the blank 20A is finally assembled in this manner, the internal structure thereof comprises a pair of spaced-apart annular channels 34 and 38 which separate, respectively, the facing sides of the sleeves 35 and 28 and the facing sides of the core 30 and inner sleeve 35. The ends of the radial outer channel 34 are closed by the bushing portions 25 of the insulating rings 27A, while the radial inner channel 38 extends between and interconnects the conducting bosses 21A.

Formed centrally on the outer sleeve 28 is an annular boss 55 that is tapped with a threaded aperture 56 and an opening 29, the latter which is adapted to register with the opening 36 in the radial inner sleeve 35. Thus, both of the channels 34 and 38 are communicable with the opening 29, and the volume of these channels can be filled with an insulating resin of a suitable free-flowing type by injecting the resin material, under pressure, through opening 29 and subsequently setting the same. It will be appreciated that the particular resin will be largely a matter of choice, the primary requirements being free-flowability, optimum insulating characteristics, and ability to remain "set" within expected temperature conditions. As a result, the inner sleeve 35 is insulated from the core 30 as well as from the outer sleeve 28 by resin insulating sleeves 39, Fig. 2, the resin also flowing into the sections of channel 38 lying between the inner ends of the bosses 21A and the ends of the sleeve 35. It will be seen that the bosses 21A are electrically interconnected through core 30 and the projections 31 thereof, and that the inner collars 26 are electrically interconnected through the inner sleeve 35. As shown in Fig. 14, the ends of the projections 31 extend beyond the bosses 21A and are adapted to be held in a lathe whereat the electrically identical end portions of the plug blank 20A can be symmetrically machined to assume the finished configuration shown in Figs. 1 and 2. The annular channels 34 and 38 are preferably filled before machining since the resin will then tend to adhere to exposed parts, especially the rubber insulator rings, and prevent rotation thereof relative to core 30 during machining. However, I have found that when the terminal bosses 21A are pressed over the knurls 33 and firmly forced toward one another to limit positions, the collars, insulating rings, and sleeves are frictionally locked to such an extent as to assure rotation of all parts with the core 30 and the projections 31 thereof during machining.

Considered from the standpoint of the internal insulating method involved and the purpose thereof, it will be appreciated that the conductor plug blank as 20A may assume several structural modifications by way of design insofar as the insulator-filled channels and the insulator rings are concerned, the essential feature being that the conductor plug blank as presently conceived may be machined in one operation and the internal conductors thereof insulated by a single step.

The jack holder 40 is generally tubular in form and preferably composed of an insulating plastic. The recess 44, in which the plug 20 is to be partially disposed, terminates at the forward end of a body portion 44 of holder 40. The rearward end of the body portion 44 is formed with a central recess 45 wherein one end of the triple conductor cord 61 terminates. A fiber shell or outer tube 60 encases the jack holder, and the open end of this housing projects beyond the forward open

end of the jack holder so as to provide an internal shoulder against which the boss 55 on the plug 20 is adapted to abut when the latter is fully and properly inserted in the jack holder. At its forward end, the housing 60 is formed with an opening which is adapted to register with the threaded aperture 56 in the boss 55 so that a set screw 57, Fig. 1, can be used to lock plug 20 against displacement from the jack holder.

When plug 20 is inserted in the jack holder, the conducting elements 21, 26 and 28 thereof are each engaged by one of three terminal contacts 50, 70 and 80 of a type generally indicated as 50, Fig. 13. These terminal contacts as 50 are mounted in position on the body portion 44 of jack holder 40 and are spaced 120° apart from each other as best shown in Fig. 8. Corresponding substantially to the spacing between the aforesaid terminal contacts, three elongated slots 42 are spaced 120° from each other about the periphery of the jack holder 40. As best shown in Figs. 1 and 12, the slots 42 terminate short of the forward end of the jack holder and open at the rearward end thereof so that portions of these slots are coextensive in length with the recess 45 at the rear of the jack holder 40. Formed intermediate the ends of each of the slots 42 are a pair of transverse slots 43 that extend into the body portion 44 of the jack holder, and it is these latter slots which function in part to maintain the terminal contacts as 50 in position on the jack holder.

While the three longitudinal slots 42 are conveniently of the same length, the terminal contacts mounted on the jack holder are formed with contact elements or springs each of different lengths. Thus, there is a terminal contact 50, Fig. 2, provided with a short contact spring 52 that is adapted to engage a conducting head 21 of the plug 20; a terminal contact 70, Fig. 7, provided with a contact spring 72 of an intermediate length adapted to engage a conducting collar 26 of the conductor plug; and a terminal contact 80, Fig. 6, provided with a long contact spring 82 adapted to engage a conducting sleeve 28 of plug 20. Each terminal contact is generally of the same configuration and, as best shown in Fig. 13, comprises a sleeve element as 51 and a pair of transverse arms as 53 which project from the contact spring as 52. The body portion 44 of the jack holder 40 is formed with recesses 47, 48 and 49 spaced 120° apart so as to afford housings for the sleeves 51, 71 and 81 of each of the three terminal contacts. When positioned on the jack holder, these sleeve elements 51, 71 and 81 rest in the corresponding housings 47, 48 and 49, and the pairs of transverse slots 43 receive the transverse arms 53, 73 and 83. The transverse arms hold the terminal contacts against horizontal displacement, and as shown in Fig. 8 vertical displacement from the jack holder is prevented by engagement between the inner sides of shell 60 and the sleeve elements 51, 71 and 81 of the terminal contacts. One end of the cord 61 is disposed in the rearwardly opening recess 45 of the jack holder 40, and lead-in conductors 54, 74 and 84 are clamped in the corresponding sleeves 51, 71 and 81 of the terminal contacts. It will be appreciated that the contact springs as 52 normally bear firmly against the corresponding conducting elements of conductor plug 20 and, when the latter is removed from the jack holder, spring part way into the longitudinal recess 41, that is to say, are inclined radially inwardly of the slots 42 when the

plug 20 is removed from the jack holder. On the other hand, as plug 20 is forced into the jack holder, the contact springs 52, 72 and 82 of the three terminal contacts are forced radially outwardly, and when plug 20 assumes its fully inserted position as defined by boss 55 engaging the outer open end of the jack holder 40 conducting sleeve 28 of the plug is electrically connected with terminal contact 80; a conducting collar 26 with terminal contact 70; and a conducting head 21 with terminal contact 50. Consequently, when current is present in the conductor cord 61 and therefor in the lead-in wires, both conducting heads 21 are charged through the interconnecting metallic core 30 and both conducting collars 26 through the interconnecting metallic sleeve 35.

From the above, it will be seen that the plug 20 can be reversed simply by loosening the set screw 57 and withdrawing the plug 20 from out of the jack holder 40, the novel arrangement between the terminal contacts and the slotted jack holder permitting reversal of the conductor plug without need for further knockdown or disassembly. In the event that one of the contact springs becomes worn or loses its resiliency, or the effectiveness of the terminal contact otherwise becomes impaired, the latter can be replaced simply by removing the outer shell 60, disconnecting the appropriate lead-in conductor, and dropping a new terminal contact into position on the body portion 44 of the jack holder. It will be seen that the terminal contacts are confined rather than fastened in position, and moreover, being spaced apart from each other, do not require insulation to prevent short circuiting.

While the aspects of the present invention have been described from the standpoint of a three conductor terminal plug, it will be appreciated that corresponding changes for other types can be made as required without departing from the concepts and scope of practice set forth. The specific composition for the various conducting elements and insulators of the conductor plug is largely a matter of choice, the preferred types being described by way of illustration rather than exclusion or limitation. The appended claims are statements of what I presently consider to be the characterizing features and manifestations which embody the novel concepts of the present invention, distinguishing the same from others in the art.

I claim:

- 55 1. In a terminal plug for use in telephone switchboards or the like, a conductor plug having symmetrical end portions whereby the conductor plug is reversible in a holder, a cylindrical holder formed with spaced apart slots on its periphery and having an elongated central recess therein for receiving the conductor plug, the elongated recess terminating at a body portion of the holder, other slots extending transversely of each of the first-named slots and extending 60 into the body portion of the holder, terminal contacts mounted on the body portion of the holder and each having a contact spring with arms extending transversely therefrom, the terminal contacts being spaced apart from each other with 65 the arms thereof positioned in the said other slots and the contact springs thereof freely disposed in the first-named slots, the contact springs being adapted to engage different conducting elements of the conductor plug, and an outer shell 70 surrounding the holder whereby the terminal

contacts are maintained in position about the body portion of the holder.

2. In the terminal plug according to claim 1, a boss located centrally on the conductor plug, the outer shell projecting beyond the corresponding end of the holder to thereby define an internal shoulder against which the boss is abuttable.

3. In a terminal plug for use in telephone switchboards or the like, a conductor plug having symmetrical end portions whereby the conductor is reversible in a holder, a tubular holder for the conductor plug having a longitudinal recess terminating at a rearward body portion in the holder, the periphery of the holder being formed with elongated spaced-apart slots and other slots extending transversely of each of the elongated slots, the said other slots also extending into the body portion of the holder, terminal contacts mounted on the body portion of the holder and each comprising a spring contact with arms extending transversely therefrom, the terminal contacts being spaced apart from each other with the spring contacts each positioned in the corresponding elongated slots and the transverse arms being disposed in the corresponding said other slots, the contact springs being adapted to engage different conducting elements of the conductor plug, and an outer shell surrounding the holder whereby the terminal contacts are maintained in position about the body holder.

4. In the terminal plug according to claim 3, a boss located centrally on the conductor plug, the outer shell projecting beyond the corresponding end of the holder to thereby define a shoulder against which the boss is abuttable.

5. A holder of the type adapted to slidably receive a switchboard plug comprising, an elongated tube-like member recessed axially to receive one end of said plug, said recess terminating short of the rear of said plug to thereby afford a body portion in the holder, a longitudinal slot formed in the periphery of said tube-like member to correspond to a conductor element of said plug, a pair of transverse slots at the rear of said longitudinal slot with one such transverse slot being formed at either side of the longitudinal slot, said transverse slots each extending down into said body portion, and a terminal contact mounted in said holder, said contact having an elongated spring contact element disposed in said longitudinal slot whereby the spring contact may move radially out and in without respect thereto, and a pair of transverse arms respectively extending at right angles from respective sides of

5 8 said spring contact, said transverse arms being seated in said transverse slots whereby said terminal contact is anchored to said holder.

6. A holder according to claim 5 comprising an outer tube removably mounted in concentric relation to said tube-like member with a portion of the underside of said outer tube engaging the top side of said terminal contact to prevent displacement of the latter relative to said holder.

10 7. A holder of the type adapted to slidably receive a switchboard plug comprising, an elongated tube-like member recessed axially to receive one end of said plug, said recess terminating short of the rear of said plug to thereby afford a body portion in the holder, a plurality of longitudinal slots formed in the periphery of said tube-like member in spaced relation one to another, each of said slots corresponding to a different conductor element of said plug, each of 15 20 25 30 35 said slots being provided with a set of transverse slots which extend down into said body portion whereby there are spaced apart sets of transverse recesses in said body portion, and a plurality of terminal contacts mounted on said body portion in said spaced relationship whereby there is afforded a terminal contact for each conducting element of the plug, each of said terminal contacts having a spring contact element disposed in a corresponding one of the longitudinal slots for movement toward and away from said recess, and each of said terminal contacts having a set of relatively short transverse arms extending from either side of the respective spring contact elements and seated in respective sets of said transverse slots whereby the terminal contacts are anchored to said body portion.

40 8. A holder according to claim 7 comprising an outer shell concentrically and removably mounted on said tube-like member, the underside of said outer shell engaging the top sides of said terminal contacts and thereby serving to prevent displacement of said terminal contacts relative to said holder.
